COMBINED SHAVING BRUSH AND DISPENSER

Willie M. Dykes, Jr., 108 Jeanette St., Cochran, Ga.

Filed Sept. 15, 1965, Ser. No. 87,003

Term of patent 14 years

(Cl. D9—2)

FIG. 1

FIG. 2

FIG. 1 is a plan view, showing my new design of a combined shaving brush and dispenser.

FIG. 2 is an elevational view thereof.

The side not shown has substantially the same appearance as the side shown.

The dominant features of my design reside in the portions shown in full lines.

I claim:

The ornamental design for a combined shaving brush and dispenser, as shown and described.
